UNITED STATES PATENT OFFICE.

LEON MONDRON, OF SALEM, WEST VIRGINIA, ASSIGNOR TO PITTSBURGH PLATE GLASS COMPANY, A CORPORATION OF PENNSYLVANIA.

EDGE-HOLDING DEVICE FOR SHEET-GLASS MACHINES.

Application filed February 16, 1924. Serial No. 693,275.

The invention relates to apparatus for use with a sheet glass drawing machine, and has for its object the provision of an improved and simplified means for preventing the edges of the sheet of glass being drawn from moving inward during the drawing operation and thus gradually reducing the width of the sheet. One embodiment of the invention is illustrated in the accompanying drawings wherein:

Figure 1 is a diagrammatic side elevation showing the drawing apparatus with which the edge holding device is preferably used, such drawing apparatus being shown in detail in the pending application of H. G. Slingluff, Serial No. 621,184. Fig. 2 is a transverse section through one side of the drawing tank showing one of the edge holding devices in side elevation. And Fig. 3 is a plan view of the device of Fig. 2.

Briefly stated, the device in its preferred form comprises a pair of squeezing or thinning pads at each edge of the sheet, which pads are intermittently caused to approach and squeeze the edges of the sheet, thus thinning it and spreading it laterally. These squeezing devices or pads are placed relatively close to the surface of the bath so that they engage the sheet while the glass is still plastic. The pads are cooled either by water or air in order to prevent them from becoming overheated and adhering to the glass and also to protect them from rapid deterioration incident to the intense heat to which they are subjected. The pads are preferably mounted so that they are free to move up with the sheet of glass during their period of engagement and their function of preventing the sheet from contracting inward is accomplished by reason of the cooling effect which they exert upon the edge and by reason of the fact that the squeezing of the edge of the sheet spreads it outward slightly, thus counteracting the normal tendency of the edge of the sheet to work inward. Gripping devices have heretofore been applied for holding the edges of a sheet, but such devices have been in the form of continuously engaging members such as rolls, or intermittently engaging tongs or pliers which grip the edge and move it outward, thus actually pulling the edge of the sheet outward as opposed to the action in my device wherein the squeezing pads are not pulled outward, but accomplish their function of work-

ing or holding the edge outward by virtue of the spreading effect on the edge incident to the squeezing. This gives an edge which is relatively continuous and uniform in a vertical plane as distinguished from an edge formed where the edge is gripped by tongs at intervals and stretched at the points where the tongs engage, as with such holding means, the edge of the sheet is made relatively irregular or wavelike in contour.

Referring to the drawings, 1 is the wall of a drawing tank or extension carrying the molten bath of glass 2 in communication with a suitable melting tank, not shown; 3 and 4 are endless belts, preferably of asbestos fabric for continuously drawing the sheet of glass 5 from the molten bath; 6 and 7 are shafts mounted upon the superstructure and driven from mechanism which drives the asbestos belts; 8 and 9 and 10 and 11 are drawing rolls, covered with asbestos fabric yieldingly engaging the glass for assisting in the drawing of such glass, such rolls being driven by means of chain connections with sprockets on the shafts 6 and 7; and 12 is one of the edge holding devices to which the present invention is particularly directed, it being understood that the other edge holding device at the opposite edge of the sheet is similar in construction and that such edge holding devices may be used in connection with any form of drawing mechanism, the form of drawing mechanism shown diagrammatically constituting no part of the present invention.

On opposite sides of the edge of the sheet 5 are arranged the squeezing or holding members 13, 13 preferably made in the form of hollow pads which may be cooled by means of air, water or other fluid circulated to and from such pads through the pipes 14, 14. These pads are arranged relatively close to the surface of the bath 2, as indicated in Figs. 1 and 2 so that they engage the edge of the sheet while it is still plastic, preferably being placed so close to the bath that their lower portions engage the tapering base or meniscus 15 (Fig. 1) of the sheet. The pads are intermittently opened and closed at intervals which may be so close together that the point of contact made by the pads on a new engagement overlaps or touches the point of engagement previously made, the character of the contacts under such conditions being indicated by the dot-

ted line on the edge of the sheet in Fig. 2. This gives an edge which is substantially uniform in thickness and has a substantially straight, vertical edge. The strain, and consequent danger of breakage, in an edge of this character is considerably less than is the case in an edge which is of irregular contour incident to gripping at separated intervals and pulling the edge outward at the points where the grippers or tongs engage as has heretofore been contemplated.

The pads 13, 13 are secured to a pair of levers 16, 16 pivoted for swinging movement in a horizontal plane toward and from each other as indicated at 17, 17. These pivotal connections are made with a pair of plungers 18, 18 mounted for sliding and rotary movement in the bearings 19, 19 carried by the standard 20, such standard being in the form of a casting resting against the side wall 1 of the furnace extension. The plungers 18, 18 may be adjusted in and out by means of screws 21, 21 which are swiveled in the casting 20 at the ends of the bearings 25 and provided with hand wheels 22, 22. In this manner, an adjustment may be made regulating the distance of approach between the spreading pads 13, 13 and the two levers with their pads may be both adjusted 30 in the same direction to accommodate the device to the sheet of glass in case the point of draw of such sheet is adjusted longitudinally of the bath a limited distance. The rear ends of the levers 16, 16 are turned inward as indicated at 23, 23 and engage sockets in the vertically adjustable bracket 24, such ends being held in the sockets by means of the rod 25 extending through the levers and carrying at its ends the adjustable nuts 40 or wheels 26, 26 between which nuts and the sides of the levers are interposed the springs 27, 27. The rear end of the base casting 20 is provided with a rearwardly projecting plate 28 for carrying the bracket 24. This plate is provided with a slot 29 in which is mounted a pair of bolts 30 which may be secured in any desired position of adjustment longitudinally of such slot. The bracket 24 is also provided with a slot 31 45 which engages the bolts 30 loosely so that the bracket 24 is free to move vertically upon the bolts as guides to a limited extent. The intermittent rocking of the levers 16, 16 toward and from each other to secure the squeezing action of the holding members 13, 13 is accomplished by means of the cam wheel 32 mounted between the two levers on an axle 33. This axle is driven by means of the bevel gears 33 and 35, the latter being mounted upon the axle 36 which is driven by means of the sprocket chain 37 passing around suitable sprockets on the shafts 36 and 7. The cam wheel 32, as indicated in Fig. 3, is provided with a thickened portion 39, so that on each revolution of

the cam wheel, the rear ends of the levers 16, 16 are pressed apart, thus causing the front ends of the levers carrying the squeezing pads to approach and grip the edge of the sheet to thin it and spread it laterally. The levers are provided opposite the cams with the usual anti-friction rollers 40, 40 for engaging the sides of the cam and a continuous yielding engagement is secured by the use of the springs 27 pressing inward upon the ends of the levers as heretofore explained.

In operation, the rotation of the cam wheel 32 continuously driven from the bevel gears 34 and 35 causes the levers to oscillate about their pivots 17, 17 so that the pads 13, 13 intermittently engage and spread the edge of the sheet, such operation being preferably timed, as heretofore indicated, so as to make a substantially continuous uniform edge upon the sheet as indicated in Fig. 2. The amount of thinning of the edge is readily regulated by means of the hand wheels 22, 22 by means of which the plungers 18, 18 carrying the pivots 17, 17 may be adjusted in and out, and may also be adjusted to position the locus of operation of the two pads longitudinally of the bath to accommodate the machine to slight movements of the sheet bodily longitudinally of the tank. Since it is not desired that the squeezing pads should interfere with the upward movement of the edge, the levers 16, 16 are mounted for free rocking movement in vertical planes so that the pads may follow along with the edge of the sheet while they are in gripping engagement therewith, and after such engagement may move back by gravity to their starting positions. This is accomplished by providing the vertically movable support for the rear ends 23, 23 of the levers 16, 16 in the form of the bracket 24 guided for vertical movement upon the two bolts 30, 30. The extent of this movement may be regulated by adjusting the bolts 30 in their slots 29 in the plate 28 upon which the bracket 24 is mounted. Various other expedients might obviously be adopted for giving the gripping members the operation as heretofore described, the invention 115 contemplating all arrangements whereby the maintenance of the edge position is accomplished by merely squeezing such edge intermittently to cause its lateral spreading without moving the gripping devices laterally. A large variety of different gripping devices might also be employed, the form illustrated, merely indicating the form which is believed to be the most satisfactory. The invention also contemplates other means 120 for cooling the pads other than the one shown.

What I claim is:

1. In combination with apparatus for drawing a glass sheet from a molten bath,

- means for preventing inward movement of the edge of the sheet, comprising a pair of engaging members on opposite sides of the sheet closely adjacent the point of formation thereof where the glass edge is plastic, and means for causing the members to intermittently engage such edge and thin it while maintaining said members against any substantial movement away from the center line of the sheet.
2. In combination with apparatus for drawing a glass sheet from a molten bath, means for preventing inward movement of the edge of the sheet, comprising a pair of fluid cooled engaging members on opposite sides of the sheet closely adjacent the point of formation thereof where the glass edge is plastic, and means for causing the members to intermittently engage such edge and thin it while maintaining said members against any substantial movement away from the center line of the sheet.
3. In combination with apparatus for drawing a glass sheet from a molten bath, means for preventing inward movement of the edge of the sheet, comprising a pair of engaging members on opposite sides of the sheet closely adjacent the point of formation thereof where the glass edge is plastic, and means for causing the members to intermittently engage such edge at the meniscus or thickened base of the sheet and thin it while maintaining said members against any substantial movement away from the center line of the sheet.
4. In combination with apparatus for drawing a glass sheet from a molten bath, means for preventing inward movement of the edge of the sheet, comprising a pair of engaging members on opposite sides of the sheet closely adjacent the point of formation thereof where the glass edge is plastic, and means for causing the members to intermittently engage such edge and thin it, the said members being free to move upward with the glass, while in engagement therewith, but being held against any substantial outward movement.
5. In combination with apparatus for drawing a glass sheet from a molten bath, means for preventing inward movement of the edge of the sheet, comprising a pair of engaging members on opposite sides of the sheet closely adjacent the point of formation thereof where the glass edge is plastic, and means for causing the members to intermittently engage such edge and thin it, the said members being free to move upward with the glass while in engagement therewith and being guided so as to move in substantially a vertical direction only.
6. In combination with apparatus for drawing a glass sheet from a molten bath, means for preventing inward movement of the edge of the sheet, comprising a pair of engaging members on opposite sides of the sheet closely adjacent the point of formation thereof where the glass edge is plastic, levers carrying said members having fixed pivotal supports permitting the levers to swing toward and from each other and also to rock in vertical planes, and means for causing the members to intermittently engage such edge and thin it.
7. In combination with apparatus for drawing a glass sheet from a molten bath, means for preventing inward movement of the edge of the sheet, comprising a pair of engaging members on opposite sides of the sheet closely adjacent the point of formation thereof where the glass edge is plastic, levers carrying said members, pivotal supports for the levers permitting them to swing toward and from each other, means whereby such supports may be adjusted toward and from each other, means for rocking the levers to cause said members to intermittently engage the edge of the glass and thin it, and means for permitting the levers to rock freely in a vertical direction so that said members may follow the upward movement of said edge during their periods of engagement therewith.

In testimony whereof, I have hereunto subscribed my name this 4 day of Feb., 1924.
LEON MONDRON.
